Primary Examiner — Kevin K Rudzinski*Assistant Examiner* — James P McKane*(74) Attorney, Agent, or Firm* — Justin Lampel(57) CLAIM

The ornamental design for an inflatable bear costume as shown and described.

DESCRIPTION

FIG. 1 is a first perspective view of a inflatable bear costume showing my new design;

FIG. 2 is a second perspective view thereof;

FIG. 3 is a front view of FIG. 1;

FIG. 4 is a rear view of FIG. 1;

FIG. 5 is a left side view of FIG. 1;

FIG. 6 is a right side view of FIG. 1;

FIG. 7 is a top plan view of FIG. 1; and,

FIG. 8 is a bottom plan view of FIG. 1.

The broken lines shown in FIGS. 1, 2, 3 and 8 define portions of the article that form no part of the claimed design.
